UNITED STATES PATENT OFFICE.

FRANCIS J. WOLFE, OF FREMONT, OHIO, ASSIGNOR TO NATIONAL CARBON COMPANY, INC., A CORPORATION OF NEW YORK.

BATTERY ELECTRODE.

Application filed May 7, 1923. Serial No. 637,328.

To all whom it may concern:

Be it known that I, FRANCIS J. WOLFE, a citizen of the United States, residing at Fremont, in the county of Sandusky and

5 State of Ohio, have invented certain new and useful Improvements in Battery Electrodes, of which the following is a specification.

This invention relates to electric cells of 10 the kind wherein one electrode comprises a pulverulent material. The invention relates more especially to the construction of cathodes for cells having a zinc anode and an alkaline electrolyte, said cathodes comprising pulverulent copper oxid which acts 15 as a depolarizer.

To overcome the relatively high resistance of copper oxid in pulverulent form, it is customary to dispose the oxid in extended 20 contact with a good conductor. Such conductor may conveniently envelop and support the oxid, and should be permeable to the electrolyte in that case. A basket of 25 perforated sheet iron, usually tinned, is used as a container for the copper oxid in a common form of such cells.

Despite the fact that the perforations in the sheet iron are small, the pulverulent copper oxid tends to sift through them, 30 both before and after the cell is assembled. In either case, the oxid which escapes from the container is lost to the cell, and when it sifts from electrodes which have not been assembled in cells it soils the hands and 35 clothing, floats in the air, and is generally objectionable.

In accordance with the present invention, the perforations of the iron container are stopped with a material which persists in 40 the cell after the latter is assembled, at least until the copper oxid is so altered by the action of the cell that its tendency to escape from the container is eliminated. The material used to stop the perforations 45 must not be readily attacked by the alkaline electrolyte; it must be impervious to very finely powdered copper oxid; and it must be permeable to the electrolyte to prevent depletion of the electrolyte in proximity to 50 the copper oxid.

Such materials as best meet the above requirements are unfortunately non-conductors. Cloth, felt or board, which are bibulous, and composed of material fairly

but such of these as are sufficiently fine in texture to retain the fine oxid are composed of non-metallic fibers, which are non-conductors, as noted above.

In accordance with my invention conductive paths joining the copper oxid and the contact member, viz, the sheet iron basket when this is employed, are provided, such paths passing through the perforation-stopping material but in such manner that no channels permitting the escape of the copper oxid result.

The invention will be more particularly described in connection with the accompanying drawing, in which

Fig. 1 is a front view of a perforated sheet iron container, lined with cloth but without the copper oxid depolarizer, a portion of the front wall of the container being broken away to show the interior; and

Fig. 2 is an enlarged section along the axis of one of the rivets 7, of Fig. 1.

The container 3 is a prism in form and has a relatively short dimension in a direction perpendicular to the plane of the paper. It is perforated throughout with holes 4 and has a complete lining of cloth 5. The lining as shown lies flat against the perforated sheet metal at all points. This result can be conveniently obtained by pasting the cloth onto the perforated sheet used in making the baskets before the sheet is cut and made up. A post 6 for supporting the cathode and making connection thereto is provided.

The conductive paths connecting the container 3 with the interior space are shown at 7, in the form of copper, iron, or coppered-iron rivets of the common split type. These rivets are inserted through registering holes of appropriate size in the basket and its lining, and upset, a complete closure of the hole provided with the rivet resulting.

In order to increase still further the proportion of the copper oxid which has a low resistance connection with the container 3, there are preferably provided, inside the container and in contact with the rivets 7, extended conductors 8. These conductors should be permeable to the electrolyte in order not to interfere with its diffusion. Small sections of wire gauze, either copper, iron, or coppered iron, are quite suitable.

It is obvious that the embodiment of the invention which has been specifically de-

scribed is subject to modification in many different ways. The invention may be applied to cells in which a non-alkaline electrolyte is employed, and to either cathodes or anodes. The pulverulent material may be, for example, an oxid of manganese or lead in a cathode, or a pulverulent metal, such as sponge lead, in an anode. The scope of the invention is limited only by the 10 appended claims.

I claim:

1. An electrode for the described purpose comprising a conductive pulverulent material, a perforated conductive envelope 15 therefor, a permeable septum of non-conducting material between the pulverulent material and the envelope, said septum being impervious to the pulverulent material, and a solid conductor electrically connecting 20 the pulverulent material and envelope.

2. The invention according to claim 1 in which the pulverulent material is copper 25 oxid.

3. The invention according to claim 1 in which the permeable septum is of fibrous 25 structure.

4. The invention according to claim 1 in which the permeable septum is a woven fabric.

5. The invention according to claim 1 in 30 which the solid conductor is arranged to give an extended contact with the pulverulent material.

6. A cathode for the described purpose comprising pulverulent copper oxid, a fo- 35 raminous metal envelope therefor, non-conducting fabric impervious to the copper oxid between the latter and its envelope, and a plurality of solid conductors electrically connecting the copper oxid and its envelope, 40 said conductors having enlarged inner ends, and said enlarged ends being permeable to the electrolyte.

In testimony whereof, I affix my signature.

FRANCIS J. WOLFE.
